(57) **CLAIM**

The ornamental design for an armored vehicle, as shown and described.

DESCRIPTION

1. Armored vehicle

1.1 :Perspective

1.2 :Front

1.3 :Right

1.4 :Rear view

1.5 :Left

1.6 :Top

1.7 :Bottom

The designs relate to military vehicles and their portions; the broken line shown is for the purpose of illustrating portions that form no part of the claimed design.

The translucent gray overlay is provided to represent portions of the armored vehicle that are disclaimed. The underlying mechanical parts and the translucent gray overlay itself form no part of the claimed design.

1 Claim, 7 Drawing Sheets
